CONTAINER

Thomas Y. Brooke, Chicago, Ill., assignor to
American Can Company, New York, N. Y., a
corporation of New Jersey

Application June 17, 1937, Serial No. 148,780

3 Claims. (Cl. 221—62)

The present invention relates to dredge or sifter top containers or cans and has particular reference to a can in which the sifter top is removably seated within a friction ring opening, the sifter top being equipped with a reenforced perforated sifter element sliding on a raised sift-proof and perforated mounting.

Although numerous varieties of dredge or sifter top cans have been made and marketed, considerable difficulty has been experienced more or less in obtaining a sifter top which is sift-proof against the escape of finely ground or pulverized materials without the use of gaskets. Ground cinnamon is particularly hard to hold and it is exceedingly difficult and many times impossible to ship or transport it in sifter top cans without having the fine cinnamon particles sift out. The can of the present invention has been found to be entirely satisfactory for such difficult materials, the sifter elements being of such rigidity and of such tight fitting qualities that sifting through is entirely prevented and this without the use of gaskets. At the same time this sifter top can is of simple and economical construction.

An object of the present invention is the provision of a dredge or sifter top can which is simple in design and economical of construction wherein the sifter top is equipped with a movable perforated sifter element rigidly reenforced against torsional stresses and held firmly and uniformly against a raised perforated mounting on which the rigid sifter element may be easily moved, to bring the sifter perforations of both element and mounting into alignment for dispensing the contents of the can, the sliding sifter joint preventing escape or sifting of the contents when the sifter perforations are in non-alignment.

Another object of the invention is the provision of a dredge top can having a sifter top of the character described wherein the sifter element is of dish shape and is reenforced by a continuous upright rim, extending around its periphery, which imparts strength and rigidity to the element as a whole and in particular prevents torsional strains and bending of the perforated base of the element to insure a better fit, the upright rim also serving as a finger-hold for moving the sifter element on its mounting.

Another object is the provision of such a sifter top for a dredge can wherein the raised and perforated mounting by reason of its being raised sets off a reenforced flat operating surface free from torsional or bending strains, the sifter element being held firmly and uniformly against

the raised mounting by elongated projections struck out from the sides of the sifter top and engaging against the top of the reinforcing rim of the sifter element so that any stresses set up by such engagement will not distort the base of the element and/or tend to draw it away from its mounting.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a dredge top can embodying the instant invention; 15

Fig. 2 is an enlarged top plan view of the can of Fig. 1, parts being broken away;

Fig. 3 is an enlarged transverse section taken substantially along the line 3—3 in Fig. 2; and

Figs. 4 and 5 are enlarged longitudinal sections taken substantially along the line 4—4 in Fig. 2, Fig. 5 showing a movable part of the can in a different position than that shown in Fig. 4. 20

A preferred embodiment of the present invention is illustrated in the drawing and is incorporated in a container or can 11 which is adapted to hold ground or pulverant material such as finely divided cinnamon and the like. The can comprises a tubular, rectangular shaped body 12 having an imperforate bottom closure member 13 and a dredge top closure member generally indicated by the numeral 14. The closure members are secured to the body in any suitable manner, as by folded seams 15. 25

The dredge top closure member 14 includes a friction ring 17 having a countersunk panel wall section 18 surrounded by a substantially vertical wall section or rim 19. The friction ring is permanently connected to the can body 12 by the upper seam 16, the outer marginal portion of the rim 19 being folded over and embodied in the seam for this purpose. 35

An elongated opening 21 having straight and parallel sides and rounded ends is provided in the panel wall section 18 centrally of the friction ring 17. This opening is used for originally filling the can and also used by the consumer for removing its contents in bulk form as by a spoon or other instrumentality. The opening is bounded by a depending friction wall section 22. 45

A removable sifter device 25 fits within the elongated opening 21 of friction ring 17 for closing the can after it is filled and for use in dispensing the can contents with a sifting action. The sifter device comprises a dish shaped mem- 50 55

ber 26 having a bottom wall section 27 which is surrounded by an upright rim or wall section 28, a small radius 29 being the connection between the wall sections. The upright wall section is of the same contour as that of the opening 21 and frictionally engages against the depending flange 22 of the friction ring 17 when the sifter device is in place within the opening 21. The upper end of the upright wall section 28 merges into an outwardly and downwardly bent flange 30 having a curled edge 31 which tightly engages against the counter-sunk panel wall section 18 of ring 17 when the sifter device is in place on the can.

15 The bottom wall section 27 of sifter member 26 is formed with a mounting or raised wall section 33 having a flat top surface. This raised wall section is provided with spaced sifter perforations 34. By reason of the wall section being raised, its 20 flat top surface is reenforced and is prevented from being affected by any bending or flexing imparted to or inherent in the bottom wall 27. This raised wall section is used as a mounting for a sifter element or slide 36.

25 Sifter slide 36 is also dish shaped and includes a flat bottom wall section 37 which is surrounded by a continuous substantially vertical rim 38, a small radius 39 connecting these wall sections together. The rim reenforces and strengthens 30 the slide as a whole, particularly stiffening the bottom wall section and preventing its distortion from any outside torsional strains which may be imposed on the slide.

The bottom wall section 37 of the sifter slide 36 35 seats against the top surface of the mounting 33. By reason of the elevation of the mounting no part of the bottom wall section 37 of the sifter slide engages against the bottom wall section 27 of the sifter member 26. The corner radius 39 of the sifter slide 36 is thereby held above and away 40 from the corner radius 29 of sifter member 26 and these parts have no fitting function. This permits the bottom wall section 37 of sifter slide 36 to seat perfectly flat against its raised mounting 33. The fit therefore does not depend, as is 45 usual upon what is likely to be an imperfect fitting together of corner radii. The bottom wall section 37 of the sifter slide is also provided with spaced sifter perforations 41 for cooperation with the perforations 34 of sifter member 26.

The width of the sifter slide 36 is such as to 50 snugly fit within the sifter member 26, its rim 38 being in sliding engagement with the upright wall section 28 of the sifter member. The slide is 55 shorter than the sifter member in order to allow space for relative sliding movement.

The slide 36 is retained in sliding position on top of its raised mounting 33 by elongated beads or lugs 45 which are preferably struck out from the upright wall section 28 of the sifter member 26. These beads are located in the straight portions of the wall section and project inwardly, extending over the top of the slide 36 on opposite sides thereof. The beads engage against the top 60 edge of the continuous reenforcing rim 38 of the slide and exert a pressure on the latter to hold it firmly against the top of the raised mounting 33. Thus any strains set up by this pressure are absorbed by the rim 38 thereby leaving the bottom 65 wall section 37 free from distortion and perfectly flat against its mounting.

70 By pushing against the vertical rim 38 of the slide 36 the latter may be slid across the top of its raised mounting 33 into different positions as 75 shown in Figs. 4 and 5. When the slide is in the

position shown in Fig. 4 the sifter perforations 34, 41 of the mounting and the slide are in alignment so that the contents of the can may be readily dispensed with the usual sifting action. When the slide is shifted to the opposite side of the sifter member as shown in Fig. 5 the sifter perforations 34, 41 are out of alignment and the can is closed against sifting.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container having a removable sifter member having a raised and perforated central portion provided with a smooth top surface and constituting an elevated mounting spaced vertically from the adjacent peripheral part of said sifter member, a sifter element having a perforated bottom wall section surrounded by a continuous reenforcing rim, said sifter element being disposed on said elevated mounting with its perforated bottom wall section firmly seated thereagainst and also being movable relative to said elevated mounting so that the perforated parts 30 of the sifter element and of the elevated mounting may be shifted into and out of sifting alignment, said removable sifter member having an upstanding peripheral wall surrounding said elevated mounting and terminating in an outwardly and downwardly inclined flange, portions of said peripheral wall on opposite sides of said sifter member being bulged inwardly to constitute integral beads for engaging adjacent portions of said reenforcing rim of said sifter element to hold the latter in firm sliding engagement with said elevated mounting of the removable sifter member.

2. A container having a removable sifter member provided with a central wall section formed with a smooth top raised portion constituting an elevated mounting spaced vertically from the adjacent peripheral part of said sifter member, said elevated mounting having a plurality of sifter perforations, and a sifter element having a bottom wall section movably seated on the top of said elevated mounting and containing a plurality of sifter perforations, said bottom wall section having a surrounding continuous reenforcing rim for stiffening the latter and for engagement as a finger-hold for moving the sifter element relative to the elevated mounting whereby the said perforations may be shifted into and out of sifting alignment, said removable sifter member having an upstanding peripheral wall surrounding said elevated mounting and terminating in an outwardly and downwardly inclined flange, portions of said peripheral wall on opposite sides of said sifter member being bulged inwardly to constitute integral beads for engaging adjacent portions of said reenforcing rim of said sifter element to hold the latter in firm sliding engagement with said elevated mounting of the removable sifter member.

3. A container comprising a body, a friction ring secured to said body, a sifter member frictionally engaged in said friction ring and having a wall section formed with a smooth top raised portion constituting an elevated mounting spaced vertically from the adjacent peripheral

part of said sifter member, said elevated mounting having a plurality of sifter perforations, and a sifter element having a bottom wall section movably seated on the top of said elevated mounting and containing a plurality of sifter perforations, said bottom wall section having a surrounding continuous reenforcing rim for stiffening the latter and for engagement as a finger-hold in moving the sifter element relative to the elevated mounting whereby the said perforations may be shifted into and out of sifting alignment, said removable sifter member having an up-

standing peripheral wall surrounding said elevated mounting and terminating in an outwardly and downwardly inclined flange, portions of said peripheral wall on opposite sides of said sifter member being bulged inwardly to constitute integral beads for engaging adjacent portions of said reenforcing rim of said sifter element to hold the latter in firm sliding engagement with said elevated mounting of the removable sifter member. 5
